ILLUSORY DISPLAY AND STORAGE CABINET

Lonnie R. Vincent, Newport Beach, Calif.

Application March 28, 1949, Serial No. 83,974

1 Claim. (Cl. 312—118)

1

This invention relates to a cabinet for displaying and storing merchandise, particularly articles of merchandise of small size, aesthetic qualities of style and beauty, and considerable value, such as may be found, for example, displayed on open counters in the cosmetic and notion departments of drug stores and department stores where the articles are available for inspection and comparison by the public. As herein described, the cabinet embodying this invention is used for the display and storage of lipsticks and their holders, but it will be understood that it is suitable and may be equally well used for the display and storage of a great variety of other articles, including jewelry, pens and pencils, cigarette and cigar holders, and many others that will occur to a merchant.

It is an object of this invention to provide a cabinet in which articles of the character above described may be displayed in a manner enhancing and accentuating their aesthetic qualities.

Another object of the invention is to provide a cabinet in which merchandise articles may not only be advantageously displayed but may also be conveniently stored in a manner not readily apparent and therefore not detracting from the aesthetic value of the display.

A further object of the invention is to provide a cabinet in which articles of merchandise may be displayed in a manner permitting demonstration to, and comparison by, a customer of their various qualities, yet making handling of the articles largely unnecessary as well as discouraging it.

Still another object of the invention is to provide a cabinet for displaying, storing, and demonstrating merchandise in which the articles on display are so arranged as quickly to indicate to a sales attendant any pilferage which may occur.

Yet another object of the invention is to provide a display cabinet affording to a customer an impression of clear visibility and accessibility of the articles contained therein and actually affording maximum visibility consistent with concealed storage of merchandise.

Further objects and advantages of the invention will be pointed out as the following description of a preferred embodiment of the invention proceeds, or will be apparent from that description and from the accompanying drawings, illustrative of that embodiment, in which:

Fig. 1 is a perspective view of a display and storage cabinet constructed according to the principles of this invention, with articles of mer-

2

chandise shown displayed, the viewpoint being towards a frontal corner of the cabinet;

Fig. 2 is an elevational view of one of the end panels of the cabinet;

Fig. 3 is a frontal elevation of the cabinet, articles of merchandise shown in Fig. 1 being omitted from this view for greater simplification and clarity;

Fig. 4 is a rear elevational view, showing bins or compartments for the storage of merchandise;

Fig. 5 is an end elevational view showing the end panel of Fig. 2 in its relation to the surrounding top, bottom, front and rear members;

Fig. 6 is a vertical sectional view, slightly enlarged, on the line of section indicated at 6—6 in Fig. 4, showing details of the top of the cabinet;

Fig. 7 is a vertical sectional view, also enlarged, on the line of section indicated at 7—7 in Fig. 4, showing details of the bottom of the cabinet;

Fig. 8 is a perspective view on a further enlarged scale of one of the merchandise racks of the cabinet; and

Fig. 9 is a vertical transverse sectional view of the merchandise rack, taken on the line of section indicated at 9—9 in Fig. 8.

Having reference now to the details of the drawings, the preferred embodiment of my invention has as its supporting members, end panels 11, one of which is shown in Fig. 2. The end panel 11 of Fig. 2 is the panel shown at the left in Fig. 1, and is preferably made of transparent plastic material or glass, and has on its inner surface a vertical groove 12 and a plurality of horizontal grooves 13 extending from the groove 12 to the forward margin 14 of the panel. It will be understood that the opposite end panel 11 is symmetrical with the panel illustrated in Fig. 2, with grooves 12 and 13 also on its inner side.

The end panels 11 are formed with T-shaped feet 15, the upper shoulders of which support a floor panel 16. The floor panel 16 may be constructed of two wooden members, notched to fit the stems of the feet 15 and meeting at the center line of the end panels 11 and held together by wooden strips 17 at the exterior of the panels 11.

A plastic roof frame member 18 connects the upper ends of the end panels 11 and has blocks 19 secured to its under side by screws 20. Plastic rods 21 connect the two end panels 11 at suitable intervals between the roof member 18 and the floor 16, and are threaded to receive screws 22.

By tightening the screws 22 in the rods 21 the end panels 11 may be compressed against the blocks 19 and the notches of the floor panel 16 to form a very simple, yet rigid and ornamental frame 23, supported on the plastic feet 15, and easily disassembled in the event that any of its members becomes broken or marred.

A mirror 25 is inserted by its lateral margins in the vertical grooves 12 of the end panels 11 and rests on the floor panel 16, concealing the joining line of the members of the floor panel. It will be observed that the mirror 25 need receive none of the strain attendant upon tightening the frame 23 to a rigid condition and is therefore not subject to distortion by compression. The mirror 25 divides the space bounded by the frame 23 into a forward compartment 26 and a rearward compartment 27 and is arranged to reflect towards the front of the frame.

Shelves 29 are supported by their ends in the horizontal grooves 13 of the end panels 11, thus dividing the forward compartment 26 into a plurality of display zones in which may be displayed articles of merchandise which will be reflected in the mirror 25. The shelves 29 are of transparent plastic or glass and, like the mirror 25, receive no end compression from the frame 23 and are therefore not easily distorted. The lowest shelf 29 preferably rests upon the floor panel 16, and may suitably be a mirror, thereby concealing all but the outer edge of the panel 16 and giving the cabinet the appearance of being constructed almost entirely of glass or plastic. All of the shelves are preferably disposed in contact with the mirror at their rearward edges.

A subsidiary frame 31 is disposed in the rearward compartment 27, dividing that compartment into bins 32 for the storage of merchandise. The frame 31 is formed of uprights 33 and shelves 34 mortised to interlock, and the shelves 34 are sloped so that the bins 32 may more easily retain round articles or cylindrical articles stacked on their sides therewithin. It is contemplated that the bins 32 will ordinarily contain merchandise of the same type as displayed on the shelves 29 in approximate alignment with each bin, so that a sales attendant may readily pick from an aligned bin an article corresponding in type to an article displayed in the forward compartment to which a customer may point. The subsidiary frame 31 may be backed by a plate 35, cemented or otherwise secured thereto, to enable the frame to be moved without first removing the contents of the bins. The plate 35 is disposed back to back with the mirror 25.

To prevent pilfering from the forward display compartment 26, a pair of sliding doors 38, of transparent plastic or glass, are mounted in a grooved track 39 secured to the roof frame member 18 and in grooves 40 cut in the upper surface of the floor panel 16 adjacent the forward margin of the panel. The doors 38 may be provided with finger grooves 41 to assist in moving them. In a similar manner, sliding doors 42 may be provided as closures for the rearward compartment 27, sliding in a grooved track 43 secured to the roof frame member 18 and in grooves 44 cut in the upper surface of the floor panel 16 adjacent the rearward margin of the panel.

The forward doors 38 of course prevent removal of the shelves 29 from the forward compartment 26, as well as preventing pilferage of merchandise from the shelves. The rearward doors 42 retain in place the whole subsidiary frame 31, which, however, may be removed as a

unit when the doors 42 are not present by pulling rearwardly its lower end so as to permit its upper end to be disengaged from behind the grooved track 43.

A cabinet constructed as above described is not only an ornamental cabinet of pleasing appearance, but a very practical combined display and storage cabinet which, because of the mirror 25, gives the appearance of being devoted entirely to display and apparently displays twice the amount of merchandise actually on its display shelves. The merchandise actually displayed on the shelves 29 may be kept to a minimum, for example, a display of lipsticks may include only one lipstick of each of a number of colors and shades. With the displayed lipsticks reduced in number and protected by the doors 38, both the temptation and the opportunity for pilferage are reduced. The storage bins 32 are not only distant from a customer standing in front of the cabinet, but their existence is concealed and apparently denied by the optical illusion provided by the mirror 25, which gives the impression that the shelves 29 extend to the full depth of the cabinet. The optical illusion is increased by the device of supporting the shelves 29 by their ends in the grooves 13 of the end panels 11. The shelves thus appear to extend beyond the mirror, their ends appearing as unbroken lines and not as obvious reflections.

The mirror 25 also eliminates the necessity for handling by a customer of such articles as lipsticks. Not infrequently a woman wishes to compare the shade of a lipstick with the shade she is wearing, and in the absence of such a mirror as the mirror 25, she will hold a sample lipstick close to her lips for comparison in her compact mirror. When lipsticks are displayed in the cabinet of my invention, she may, without touching the sample lipsticks, quickly align the reflection of her lips with each actual sample, and with the reflection thereof, of a large number of different shades. There is, therefore, no need for the transparent doors 38 to be opened, or for handling of the samples, both the exposure and the handling being often unsanitary and leading to theft.

As a further safeguard against pilferage and as an aid to display merchandising, I may provide racks 50 for holding merchandise articles such as lipsticks. The racks 50 are formed of sheets of transparent plastic material and may be bent in V-shaped channels having rounded webs and adapted to rest upon one arm of the channel. The other, or upper arm 51 is perforated by a plurality of holes 52, of a size suitable to receive the articles to be displayed, for example the cylindrical cases or holders commonly used to contain lipsticks, the uncovered ends of the lipsticks then projecting upwardly above the rack. These cases usually bear shade numbers or other identifying marks on their bases or ends, and as the bases of the cases rest upon the transparent supporting arms 53 of the racks 50, the identification marks are clearly visible therethrough. Consequently, it is again not necessary for either a customer or a sales attendant to handle the individual lipsticks. When a customer has selected the shade or shades of lipstick which she desires, the rack 50 containing the particular shade may be lifted as a unit from the shelf 29 on which it rests, the identification may be read through the transparent arm 53, and delivering of merchandise of identical characteristics may be made from the storage bins 32. The entire

rack 50 being transparent, such details of interest as the manufacturer's name or trademark and the ornamentation of the lipstick case are readily visible.

As it is unnecessary to remove a lipstick from the racks 50 emptiness of a hole 52 is an immediate indication of unnecessary handling or of pilferage. The racks also hold lipsticks isolately, and forwardly in proximity to the doors 38, so that each lipstick may appear in the mirror 25 in juxtaposition to the lips of a person standing close to the doors. When the transparent racks are placed on the shelves with their open edges in contact with the mirror 25, they appear to extend without noticeable break beyond the mirror, and the optical illusion of a deep cabinet is much enhanced. The curved closed edges of the racks, while refracting light to some extent, do so irregularly because of their roundness, and do not produce any sharp break in the light or noticeable distortion of the articles held by the racks. The racks 50 therefore combine with the transparent, mirrored, display-and-storage case, which encloses them, to accomplish the objects and purposes of the invention to a higher degree than if the merchandise were loosely arranged upon the shelves 29. It is also to be noted that orderly and spaced arrangement of the merchandise in the racks 50 permits a better view and identification of the merchandise.

Obviously my invention is subject to modifications in form and arrangement, therefore I do not choose to be limited to the exact embodiment herein described and illustrated, but rather to the scope and spirit of the invention as set forth in the appended claim.

I claim:

In a cabinet for displaying and storing lipsticks and similar articles: a box-like frame having

opposed open sides and vertical end walls; a vertical partition dividing the space defined by said frame into a forward display compartment and a rearward storage compartment and having a reflecting surface on its forward side; said end walls being of transparent material and having vertically spaced horizontal grooves on their interior surfaces extending to said reflecting surface; shelves in said forward compartment supported in said grooves, said shelves abutting said reflecting surface whereby an illusion of depth of said compartment is achieved; a transparent door on the open side of said forward compartment through which the lips of a person standing before said cabinet may be compared in said reflecting surface to lipsticks held on said shelves while said door remains closed; and a display rack placed on said shelves, having a marginal portion closely adjacent said reflecting surface so as to further achieve the aforesaid illusion, said rack having holes for the reception of individual articles displayed therein and being transparent to permit reading of markings on portions of said articles within said holes while said door remains closed.
